UNITED STATES PATENT OFFICE.

WILLIAM P. BROWN, OF MINNEAPOLIS, MINNESOTA.

SHOTGUN-SHELL.

1,034,684.

Specification of Letters Patent.

Patented Aug. 6, 1912.

Application filed March 24, 1911. Serial No. 516,765.

To all whom it may concern:

Be it known that I, WILLIAM P. BROWN, of Minneapolis, Hennepin county, Minnesota, have invented certain new and useful 5 Improvements in Shotgun-Shells, of which the following is a specification.

The object of my present invention is to prevent the gas from the burning powder from filling the wall of the shell between it 10 and the inner metallic sleeve or lining. Ordinarily in shot gun shells as usually constructed, the gas can work its way between the paper shell and the inner cylinder or sleeve and loosen the paper from 15 its seat in the cap.

My invention consists generally in providing the inner shell or sleeve with one or more annular ribs which are pressed into the surface of the paper shell and form an 20 effectual barrier against the passage of gas between the shell and the sleeve.

In the accompanying drawing forming part of this specification, Figure 1 is a longitudinal, sectional view of a shot gun shell 25 with my invention applied thereto, Fig. 2 is a similar view showing the coöperating ribs formed in the inner and outer sleeve of the shell.

In the drawing, 2 represents the cap of 30 the shell or the outer cylinder, into which the end of the cylindrical paper portion 3 is inserted.

4 is a disk, usually of paper, inserted into the end of the cylinder 3 and provided with 35 the ordinary fulminating cap socket 5, as usual in shells of this kind.

6 is an inner sleeve fitting snugly within the end of the paper cylinder and having its outer edge bent inwardly to bear on the 40 surface of the disk. The paper cylinder is gripped between the outer cylinder 2 and the sleeve 6 and to prevent the passage of gas between the paper cylinder and the inner sleeve I provide annular grooves 7 in the sleeve forming ribs on its outer surface, which are forced into the paper cylinder and form close gas-tight joints therewith, thereby preventing the gas from passing to the rear end of the shell and unsealing 45 the paper cylinder. I have also found that the gas, in working back between the lining and the paper cylinder, will expand the outer cylinder near the head to such an extent that it is almost impossible to remove 50 the shell from the gun. By providing the

ribs in the lining so that annular, non-communicating grooves will be formed in the paper cylinder, I am able to effectually prevent the passage of the gas between the lining and the cylinder. These ribs are endless, as indicated in the drawing, and the passage of gas between the lining and the paper cylinder is made practically impossible. In Fig. 1 I have shown two of these annular grooves, but a greater or less number of them may be provided, according to the size of the shell and the requirements for forming a tight joint.

In Fig. 2 I have shown a modification which consists in providing a single groove 70 in the inner sleeve and two grooves 8 in the outer sleeve or cylinder 2. The grooves 8 are preferably arranged on each side of the groove in the sleeve so that the paper cylinder will be gripped and held between them and the passage of gas between the inner cylinder and the sleeve will thereby be effectually prevented.

I claim as my invention:—

1. A shot gun shell comprising a head 80 and a cylinder or sleeve formed thereon, a paper cylinder having one end fitting within said sleeve and seated against said head, a breech wad, between which and said sleeve the inner end of said cylinder is gripped, 85 a metallic lining for the inner portion of said cylinder extending between said breech wad and said cylinder, the forward portion of said lining projecting beyond said breech wad and inclosing the powder chamber, 90 said lining having an internal annular groove forming an external, continuous rib extending around said lining, said rib being embedded in the wall of said cylinder and forming a barrier to the passage of gas 95 between said cylinder and lining.

2. A shot gun shell comprising a head and a cylinder or sleeve formed thereon, a breech wad, a paper cylinder having one end inserted between said sleeve and said 100 breech wad, a metallic lining for the inner portion of said paper cylinder having its inner end inserted between said breech wad and said paper cylinder, the outer end of said lining projecting beyond said breech wad and inclosing the powder chamber, said 105 lining having an internal annular groove formed therein forming an external, continuous rib that is seated in the inner surface of said paper cylinder, said rib form- 110

ing a barrier to the passage of gas between
said lining and paper cylinder and said
sleeve having external annular grooves
forming internal ribs on opposite sides of
5 the corresponding rib in said lining and co-
operating therewith to grip said paper cyl-
inder.

In witness whereof, I have hereunto set
my hand this 1st day of March 1911.

WILLIAM P. BROWN.
